CLAIM

The ornamental design for a sunglass storage case, as shown and described.

DESCRIPTION

FIG. 1 is an elevational right-side view of a sunglass storage case in accordance with the present invention;

FIG. 2 is an elevational front view of the sunglass storage case of FIG. 1;

FIG. 3 is an elevational left-side view of the sunglass storage case of FIG. 1;

FIG. 4 is a top plan view of the sunglass storage case of FIG. 1;

FIG. 5 is a bottom plan view of the sunglass storage case of FIG. 1;

FIG. 6 is an elevational rear view of the sunglass storage case of FIG. 1; and,

FIG. 7 is a perspective view of the sunglass storage case of FIG. 1.
